CARTON FEEDING MECHANISM

Charles F. Richard, Battle Creek, Mich., assignor to Johnson Automatic Sealer Co., Ltd., Battle Creek, Mich., a limited partnership association of Michigan

Application April 23, 1938, Serial No. 203,928

19 Claims. (Cl. 271—43)

This invention relates to devices for feeding carton blanks in knocked-down or collapsed form from a supply of such blanks to a carton making machine, and more particularly to carton feeders of the magazine type wherein the blanks are stacked on edge in substantially vertical position and are fed to the carton forming mechanism by a sliding movement parallel to the flat surfaces of the blanks as they stand in the magazine.

10 One of the objects of the invention is to provide a new and improved form of magazine type carton feeder which will be efficient, dependable and rapid in operation, and especially well adapted for use with high speed, continuous motion carton making machinery.

Another object is to provide a novel form of conveyor mechanism for advancing the carton blanks in a magazine to the feeding or transfer position, which mechanism is so constructed and controlled as to limit the advance of the foremost blank in the stack to a predetermined position so as to insure accurate operation of the feeding means.

A further object is to provide a blank feeding 25 or transfer mechanism of novel construction which is movable in the line of advance of the carton blanks so as to automatically adjust itself to the exact position of the foremost blank in the stack, and which, by its movements, controls the 30 operation of the conveyor mechanism of the magazine.

Still another object is to provide a new and improved form of transfer mechanism which is especially constructed to compensate for variations 35 in the shape of carton blanks due to bowing or warping, and to thereby insure continuous feeding in spite of differences in the characteristics of individual blanks.

A still further object is to provide a carton 40 blank feeder of the magazine type which is readily adjustable for use with cartons of various sizes.

These and other objects will appear more fully upon a consideration of the detailed description 45 of the embodiment of the invention which follows. Although only one specific form of machine has been described and illustrated in the accompanying drawings, it is to be expressly understood that these drawings are for purposes of 50 illustration only and are not to be construed as defining the limits of the invention, reference being had for the latter purpose to the appended claims.

55 In the drawings, wherein like reference char-

acters indicate like parts throughout the several views:

Fig. 1 is a side elevation of one form of magazine type carton feeding mechanism embodying the present invention;

Fig. 2 is a plan view of the mechanism of Fig. 1;

Fig. 3 is an end elevation looking from the right in Fig. 1, and including a section through the driving cams taken substantially on line 3—3 in the latter figure;

Fig. 4 is a transverse sectional view taken substantially on line 4—4 of Fig. 2;

Fig. 5 is an enlarged sectional side view of a portion of the feeding end of the mechanism taken substantially on line 5—5 of Fig. 2;

Fig. 6 is a fragmentary sectional plan view showing certain of the details of the transfer mechanism and taken substantially on line 6—6 of Fig. 5; and

Fig. 7 is a transverse sectional view taken substantially on line 7—7 of Fig. 5.

The carton feeding mechanism of the present invention comprises as its principal elements a magazine for supporting a supply of knocked-down or collapsed carton blanks stacked on edge in substantially vertical position, an intermittently operative, positively actuated conveyor for advancing the blanks toward a feeding position at one end of the magazine, a floating or pivoted transfer device movable in the line of advance of the blanks and including a transversely slid able feeding member adapted to engage one edge of the foremost carton in the stack and to slide it sideways out of the magazine, and a control mechanism operatively connected with the movable transfer device for temporarily rendering the magazine conveyor inoperative to advance the carton blanks whenever the foremost blank in the stack advances beyond a predetermined position.

While a feeder of this character may be used in connection with carton forming machines of various constructions, it is particularly well adapted for use with high-speed, continuous motion machines of the type wherein the collapsed carton blanks are delivered by the feeder to horizontally movable pockets in which the blanks are opened and squared out and from which they are loaded onto continuously moving forming blocks, the latter then carrying the blanks during the bottom closing operation.

However, since the carton making machine is not itself an essential part of the present invention, it is unnecessary to illustrate or further describe the same.

Referring now to the drawings, and specifically

to the magazine construction shown best in Figs. 1-4, it will be seen that the bed plate 11 of the magazine is supported on standards 12 by means of a pair of threaded rods or adjusting screws 13 fixed at their upper ends to the bed plate and extending downwardly through internally threaded sprocket carrying members 14 which are rotatably supported at their lower ends on the cross members 15 of standards 12. By rotating the sprocket carrying members 14, which are suitably held against upward movement on the threaded portions of adjusting screws 13, the bed plate 11 and the entire magazine construction supported thereby may be raised and lowered to assist in adjusting the magazine for use with different sizes of carton blanks.

To this end, the sprockets of members 14 are interconnected by a driving chain 16, and one of the sprocket carrying members 14 (the right-hand one in Fig. 1) is suitably connected in any desired manner for rotation with a bevel gear 17 rotatably mounted with respect to adjusting screw 13 below cross member 15 and meshing with a second bevel gear 18 which is secured to a shaft 19 extending longitudinally, and beyond the feeding end, of the magazine. The shaft 19 is suitably journaled at one end in a bearing 20 supported from cross member 15 and at the other end in a bearing 21 which may conveniently be mounted on the frame 22 of the carton making machine with which the feeder is associated. The shaft 19 has secured thereto a suitable hand wheel 23 by means of which the magazine raising and lowering mechanism may be operated. In order to assist in properly supporting the magazine, the bed plate 11 is also provided with four downwardly extending guide rods 24 which are slidably received in suitable guides 25 carried by the standards 12.

At the forward or feeding end of the magazine, the bed plate 11 has secured thereto a pair of bearing brackets 26 and 27 in which is journaled the drive shaft 28 of the magazine conveyor mechanism. Fixed to drive shaft 28 for rotation therewith, but adjustable axially therewith, are three sprocket wheels 29, 30 and 31, sprockets 29 and 30 lying between bearing brackets 26 and 27 while sprocket 31 is mounted on the extended end of drive shaft 28 which projects outwardly beyond bearing bracket 26 and the side edge of bed plate 11 (to the left as viewed in Fig. 3). To the opposite end of bed plate 11 is secured a double bearing bracket 32 which rotatably supports in longitudinally adjustable bearings a shaft 33 on which are mounted three more sprocket wheels 34, 35 and 36, complementary to those indicated at 29, 30 and 31 and so arranged on the shaft 33 as to be coplanar with the latter.

Passing around sprocket wheels 29 and 34 is an endless conveyor chain 37; sprocket wheels 30 and 35 are also connected by a similar chain 38. The upper reaches of conveyor chains 37 and 38 travel on top of and are supported by a pair of longitudinally extending bars 39 and 40, which are mounted above the upper surface of bed plate 11 by means of suitable brackets 41, said brackets being so constructed as to permit the adjustment of supporting bars 39 and 40 toward and away from one another when adjusting the magazine to handle different size cartons. As shown best in Figs. 4 and 5, the carton blanks, indicated generally at 42, are supported on edge in a stack on top of the upper reaches 75 of conveyor chains 37 and 38.

In order to hold the carton blanks in substantially vertical position as they are supported on conveyor chains 37 and 38, one or more removable backing plates 43 may be associated with the conveyor mechanism of the magazine, these backing plates being supported vertically and connected to the conveyor chains in any suitable manner. In the embodiment illustrated, the backing plates may take the form indicated at 43 in Fig. 4, consisting of a plate of a width 10 slightly less than the width of the carton blanks but extending upwardly above the tops of the blanks and having a lateral projection 44 on which is provided a downwardly extending lug 45 adapted to enter into the link openings of a third chain 46; the bottom edge of the backing plate is also provided with similar lugs for insertion into the link openings of conveyor chains 37 and 38. As indicated in Fig. 1, the lower reach of chain 46 passes around sprocket wheels 31 and 36, while its upper reach passes around a pair of idler sprockets 47 and 48 rotatably supported in elevated position by brackets 48 and 49 mounted on double bearing bracket 32 and the forward end of bed plate 11, respectively. 25 Bracket 49 also carries a third idler sprocket 50 around which chain 46 is passed in order to avoid interference with other elements of the feeder mechanism. The upper reach of chain 46 travels over a longitudinally extending bar 51 secured to the upper ends of supporting brackets 52 which extend upwardly from and are secured to the bed plate 11. By engaging the lugs of the backing plates 43 with chains 37, 38 and 46 in the manner indicated in Fig. 4, the plates 35 are both supported in vertical position and connected to the conveyor mechanism for movement therewith. It will be understood that any desired number of backing plates may be used in the magazine, each one being removed when 40 it approaches the feeding end of the magazine and replaced at the opposite end behind a new supply of carton blanks. In this way, the supply of blanks in the magazine may be replenished from time to time without stopping the machine 45 or interfering with the feeding operation.

In order to afford proper lateral support and guidance for the carton blanks as they are moved toward feeding position, a pair of side guide rails 53 and 54 are provided, guide rail 53 being mounted in a fixed position on inwardly off-set portions of supporting brackets 52 while guide rail 54 is carried by a plurality of supporting brackets 55 which are adjustable in a transverse direction relatively to bed plate 11 55 to compensate for carton blanks of different widths. As shown best in Fig. 4, the lower ends of brackets 55 are provided with internally threaded bosses 56 through which pass threaded adjusting shafts 57 journaled in suitable bearings 58 secured to the bottom of bed plate 11. At one end (the left-hand end as viewed in Fig. 4) each of adjusting shafts 57 is provided with a sprocket 59, these sprockets being connected by a driving chain 60 which also passes 60 around a pair of idler sprockets 61 and 62 suitably supported from bed plate 11. The opposite end of one of shafts 57 (the left-hand one as viewed in Fig. 2) has secured thereto a suitable adjusting hand wheel 63. Each of supporting 70 brackets 55 is also provided with a guide rod 64 which is slidably received in a bore 65 passing transversely through bed plate 11.

The conveyor chains 37 and 38, and the stacked carton blanks supported thereon, are intermit- 75

tently advanced toward the feeding end of the magazine by a positively applied force normally operative once during every cycle of the machine. In the embodiment illustrated, the step-by-step advance of chains 37 and 38 is effected by a pawl and ratchet actuation of driving shaft 28. As illustrated in Fig. 1, the end of shaft 28 which extends outwardly beyond bearing bracket 26 has fixed thereto a ratchet 66 on the hub of which is rotatably mounted an arm 67 carrying a pawl 68. The pawl 68 is continually urged into engagement with the teeth of ratchet 66 by means of a suitable spring 69. The outer end of pawl carrying arm 67 has an adjustable stud and toggle joint connection with the upper end of a connecting rod 70 the lower end of which is toggle connected to one end of a lever 71 fulcrumed in any suitable manner on the frame 22 of the carton making machine. The opposite end of lever 71 carries a cam roll 72 which is continually urged by a spring 73 toward contact with the contour of an open cam 74 mounted on and driven by a shaft 75. The shaft 75 may also be journaled in the frame 22 of the carton making machine, and is suitably driven in synchronism with the other elements of that machine.

With this construction, rotation of cam 74 normally produces one oscillation per cycle of the pawl carrying arm 67 which in turn intermittently rotates conveyor driving shaft 28 through an angle such as to advance the conveyor chains 37 and 38 a distance equal to the average thickness of a collapsed carton blank. If all carton blanks were of exactly the same thickness and were uniformly stacked in the magazine, this mechanism would automatically and successively advance the individual blanks to exactly the proper feeding position. However, it has been found in practice that carton blanks are often warped or bowed, do not always stack uniformly, and sometimes differ in thickness, the result being that a uniform advance of the conveyor mechanism does not insure a uniform position of the foremost blank in the stack. In such a situation, if the transfer or feeding mechanism is fixed relatively to the magazine in the line of advance of the blanks, improper feeding may result. To overcome this difficulty, the present invention provides a transfer mechanism which is floating or movable relatively to the magazine in the line of advance of the blanks so as to always properly contact the foremost blank in the stack, and is also provided with a control which temporarily renders the conveyor advancing means inoperative whenever the foremost blank in the stack is advanced beyond a predetermined position.

Before proceeding with a description of the transfer and control mechanism of the present invention, it may be pointed out that, as the conveyor chains 37 and 38 pass around sprockets 29 and 30, the carton blanks are delivered onto a supporting plate 76 which is mounted on bearing brackets 26 and 27 and inclined slightly upwardly toward the transfer mechanism, extending a suitable distance beyond the position of furthest advance of the foremost blank in the stack so as to provide a proper support for the blanks as they approach the feeding position. There is also provided an upper guide or hold-down plate 77 which is vertically adjustable to accommodate blanks of different heights, this plate being supported by a bracket 78 which extends laterally beyond the edges of the blanks

at one side of the magazine so as to receive a pair of vertical guide rods 79 extending upwardly from and secured to the bed plate 11. A side guide plate 80 of a height at least equal to the tallest carton blank with which the magazine 5 is intended to be used may also be provided for aligning the side edges of the blanks which are to be engaged by the transfer mechanism during the feeding operation. The plate 80 may be mounted on side guide rail 84, and is suitably 10 cut out so as to avoid interference with the transversely slidable elements of the transfer mechanism next to be described.

As shown best in Figs. 1, 3 and 5, the entire transfer mechanism is supported on a shaft 81 15 which is journaled in and supported by a bearing bracket 82 fixed to and curving downwardly and outwardly from the forward end of bed plate 11. Fixed to shaft 81 by means of a pair of laterally separated bosses 83, located one on each side of the bearing in bracket 82, is a generally H-shaped supporting arm 84 carrying at its upper end in another pair of bearing bosses 85 a rocker shaft 86 on which is mounted the feeding mechanism proper. This latter 25 mechanism comprises a feeding head 87 fixed to shaft 86 for pivotal movement about the axis thereof relatively to supporting arm 84, which head is provided with a rectangular frame 88 so constructed as to form a slideway or channel 30 for a transversely reciprocable slide member 89. The slide member 89 is held in the slideway of frame 88 by a pair of upper and lower gibs 90 secured to and extending the length of said frame. Suitably fixed to slide member 89, and projecting inwardly toward the front of the stack of carton blanks in the magazine, are a pair of brackets 91 and 92 provided with enlarged, transversely extending blocks or heads 93 and 94, respectively, the inner faces of which 40 are recessed to receive carton blank pusher plates 95 and 96. Slide bracket 92 is so constructed as to extend upwardly above slide bracket 91 in such a manner as to position pusher plate 96 directly above, but spaced vertically from, 45 pusher plate 95.

As shown best in Fig. 6, the carton engaging inner vertical face of each of pusher plates 95 and 96 is stepped to provide a shoulder 97 of a width slightly less than the thickness of an 50 average carton blank, these shoulders 97 being adapted to engage one of the vertical edges (the right-hand edge as viewed in Fig. 3) of the foremost blank in the stack and to slide the blank sideways out of the magazine when the 55 slide member 89 and the elements carried thereby are reciprocated relatively to feeding head 87 in the manner subsequently described. In order to insure engagement of the shoulders 97 with the blank edge even though the latter may be 60 warped or bowed, each of the pusher plates 95 and 96 is pivoted at one end on a stud 98 carried by the associated block 93 or 94, and a suitable compression spring 99 is utilized to urge the plate outwardly about its pivot stud toward the foremost blank in the stack. As shown, the compression springs 99 may be housed in recesses 100 formed in blocks 93 and 94 so as to thrust against the backs of pusher plates 95 and 96, the latter being provided with pins 101 70 extending outwardly through springs 99 and carrying at their outer ends stop nuts 102 which, by engagement with suitable surfaces formed on blocks 93 and 94, limit the inward movement of the pusher plates. 75

In order to properly position the transversely slidable elements of the feeding mechanism relatively to the foremost carton blank in the stack, the feeding head 87 is provided with suitable stop means for contacting the outer surface of said blank. As shown, a pair of vertically spaced, horizontally extending stop bars 103, the inner vertical surfaces of which are adapted to rest against the face of the foremost carton in the stack, are mounted on spacers 104 fixed to gibbs 90. The frame 88 of feeding head 87 also supports by means of spacers 105 a horizontally disposed stop plate 106 the inner edge of which is likewise adapted to contact the face of the foremost carton in the magazine. The pusher plates 95 and 96, stop bars 103 and stop plate 106 are so adjusted relatively to one another that the bases of the blank engaging shoulders 87 are normally coplanar with the blank contacting portions of the bars 103 and plate 106.

In order to continually urge the entire transfer mechanism toward the magazine so as to properly position the feeding elements thereof the shaft 81 upon which supporting arm 84 is secured has fixed to one of its ends (the right-hand end as viewed in Fig. 3) an arm 107 extending in a substantially horizontal plane inwardly beneath the magazine, on which arm is mounted a counterweight 108. The weight 108 is of such mass and so positioned on arm 107 as to slightly overbalance the weight of the transfer mechanism and urge shaft 81 and all of the elements supported thereby in a counterclockwise direction. In order to limit the inward movement of the transfer mechanism toward the magazine, supporting arm 84 is provided with a suitable stop lug 109 which is adapted to contact with an upwardly extending stop member 110 carried by bearing bracket 82.

Since it is necessary for proper feeding to maintain the slide member 89 and the other carton engaging elements of the feeding mechanism in vertical position regardless of the angular position of the transfer mechanism with respect to the axis of shaft 81, feeding head 87 is provided with a horizontal, outwardly extending tail piece 111 the outer end of which is connected by a link 112 to the outer end of an extension 113 of bearing bracket 82. The pivotal connections of the ends of link 112 to tail piece 111 and extension 113 are so located that their axes are in the same horizontal planes with those of shafts 86 and 81, respectively, and are equidistant from the latter. With this construction, a parallel link arrangement is provided which insures retention of the feeding mechanism in a vertical plane regardless of the angular position of supporting arm 84.

In order to reciprocate the slide member 89 and pusher plates 95 and 96 in timed relation with the elements of the carton making machine, the slide member has pivotally connected thereto the upper end of a substantially L-shaped connecting link 114 (Fig. 3), the lower or horizontal arm of said link being provided with a plurality of holes 115 to enable an adjustable connection to the vertical arm of a bell crank lever 116 which is fulcrumed on a stud 117 carried by a downwardly projecting portion 118 of feeding head 87. The other or horizontal arm of bell crank lever 116 is connected by universal joints 119 and 120 and a rod 121 to the outer end of an arm 122 fixed to one end (the right-hand end as viewed in Fig. 3) of a rocker shaft 123 journalled in a suitable bearing carried by

bearing bracket 82. The opposite end of rocker shaft 123 has fixed thereto an arm 124 which, through a compound, adjustable connecting rod 125, is connected to one end of a lever 126 which, like lever 74, may be suitably fulcrumed on the frame 22 of the carton making machine. The other end of lever 126 is provided with a cam roll 127 which projects into and travels in the groove of a closed cam 128 fixed to cam shaft 75. As previously described, shaft 75, upon which is also mounted the magazine conveyor actuating cam 74, is driven in timed relation with the elements of the carton making machine. In this manner, the reciprocating movements of the slidable feeding elements of the transfer mechanism are synchronized both with the advancing movements of the magazine conveyor and the operations of the carton forming machine.

As the individual carton blanks are slid sideways out of the magazine by pusher plates 95 and 96, they are delivered to the carton making machine in any suitable manner, as by feeding rollers indicated diagrammatically at 129 and 130. In order to prevent the transfer of more than one carton at a time, rocker shaft 86 has secured to one end thereof (the left-hand end as viewed in Fig. 3) a supporting arm 131 extending inwardly closely adjacent the side edge of bed plate 11 and carrying at its inner end an upwardly projecting bracket 132 to which is adjustably secured a separator member 133. The inner vertical surface of separator member 133 is adapted to contact the edges of the carton blanks opposite those adjacent side guide plate 80, while the edge 134 of said separator member is so adjusted with respect to stop bars 103 and stop plate 106 by means of an adjusting screw 135 as to permit only one blank at a time to pass by said edge out of the magazine.

With the mechanism thus far described, it will be apparent that, once in every cycle of cam shaft 75, the transversely slidable feeding elements of the transfer mechanism will remove the foremost carton blank in the stack from the magazine by sliding it sideways to the left as viewed in Fig. 3, and conveyor chains 37 and 38 will be positively advanced through a predetermined distance by the pawl and ratchet drive of shaft 28 so as to move all of the cartons in the stack forward a distance approximately equal to the thickness of an average blank. However, as previously stated, the characteristics of individual blanks vary, with the result that the foremost blank in the stack does not always occupy exactly the same position. While the transfer mechanism of the present invention, because of its floating character, compensates for these variations, it is desirable that the position of the foremost blank in the stack be maintained within limits to insure accurate feeding to the carton making machine. To this end, the mechanism also includes control means for temporarily ceasing the intermittent movement of the conveyor mechanism whenever the foremost carton in the stack is advanced beyond a predetermined position.

As shown, this control is effected by securing to one end of shaft 81 (the left-hand end as viewed in Fig. 3) an arm 136 which extends substantially horizontally inwardly beneath the end 70 of driving shaft 28 on which is mounted ratchet 66. The inner end of arm 136 is connected by toggle joints 137 and 138 and connecting rod 139 to another arm 140 which is pivotally mounted at its left-hand end (Fig. 1) on a stub shaft 141 75

journalled in a bearing 142 secured to the bottom of bed plate 11, the toggle joint 138 being connected to arm 140 intermediate its ends. The opposite end of arm 140 carries a latch member or detent 143 which is so designed that, when elevated to a predetermined position, it lies in the path of oscillation of a stop stud 144 carried by and projecting downwardly from pawl carrying arm 67.

0 Normally, the pawl carrying arm 67 is moved positively in a clockwise direction by the high part of cam 74 so as to advance the conveyor chains 37 and 38, and is returned in counter-clockwise direction without actuation of the conveyor mechanism by the spring 73. However, when the foremost carton in the stack advances to such a position as to cause the transfer mechanism to move outwardly in the line of advance of the blanks, and the supporting arm 84 and shaft 81 to rotate in a clockwise direction, sufficiently to elevate the detent 143 into the path of oscillation of stop stud 144, the latter will be engaged by the detent and the pawl carrying arm 67 thereby held against resetting under the influence of spring 73. The conveyor mechanism will then remain stationary until the feeding of one or more blanks out of the magazine permits the transfer mechanism to again move inwardly in a counterclockwise direction with respect to the axis of shaft 81 sufficiently to drop the latch member or detent 143 out of the path of oscillation of stop stud 144, whereupon the intermittent actuation of the conveyor mechanism will be resumed.

15 There is thus provided by the present invention an improved form of magazine type carton feeder embodying a transfer mechanism of novel construction which is movable relatively to the magazine so as to automatically adjust itself to the exact position of the foremost blank in the stack, and which is so constructed and arranged as to render the operation of the carton advancing means of the magazine responsive to its movements in the line of advance of the carton blanks. The feeding means of the transfer mechanism is also of novel construction, being operative in timed relation to the other elements of the machine regardless of the position of the transfer mechanism relatively to the magazine, and including means for compensating for variations in shape of the carton blanks so as to insure continuous feeding thereof in spite of differences in the characteristics of individual blanks. These and other features, including the ready adjustability of the feeder to accommodate cartons of different sizes, result in an efficient and reliable mechanism which is particularly well adapted for use with high speed, continuous motion carton making machinery.

60 Although only one specific form of mechanism has been described and illustrated in the accompanying drawings, it will be obvious that the invention is not limited to the exact structure shown but is capable of a variety of mechanical embodiments. For example, the construction of each of the various groups of elements specifically described may be varied by substituting equivalent mechanism for those illustrated, particularly as regards the various link, lever and shaft arrangements by which movements of the various elements are transmitted from one to the other. It is also obvious that certain of the features of the invention, such as the floating transfer mechanism and the adjustable feeding elements, are susceptible of use in other combina-

tions than that in which they are found in the embodiment herein disclosed. Various other changes, which will now suggest themselves to those skilled in the art, may be made in the form, details of construction and arrangement of the parts without departing from the spirit of the invention. Reference is therefore to be had to the appended claims for a definition of the limits of the invention.

What is claimed is:

1. In a carton feeding mechanism of the magazine type wherein a supply of collapsed carton blanks is supported in a substantially horizontal stack with the blanks on edge in substantially vertical position and wherein conveyor means are provided for advancing the blanks in said stack to feeding position, transfer means for successively removing individual blanks from said stack including a feeding member, a support for said feeding member, means for reciprocating said feeding member relatively to said support in a direction transverse to the line of advance of said blanks, stop means carried by said support and adapted to rest at all times against the foremost blank in said stack, means for mounting said support for movement in the line of advance of said blanks, and means responsive to the movements of said support in the line of advance of said blanks for controlling the operation of said conveyor means.

2. In a carton feeding mechanism of the magazine type wherein a supply of collapsed carton blanks is supported in a substantially horizontal stack with the blanks on edge in substantially vertical position and wherein conveyor means are provided for advancing the blanks in said stack to feeding position, a transfer mechanism for successively removing individual blanks from said stack including a feeding member, a support for said feeding member, means for reciprocating said feeding member relatively to said support in a direction transverse to the line of advance of said blanks, means for mounting said support for movement in the line of advance of said blanks, stop members carried by said support adapted to rest at all times against the foremost blank in said stack and thereby determine the position of said support, and means for temporarily rendering said conveyor means inoperative to advance the blanks whenever said support is moved beyond a predetermined position in the same direction as the advance of said blanks.

3. In a carton feeding mechanism of the magazine type wherein a supply of collapsed carton blanks is supported in a substantially horizontal stack with the blanks on edge in substantially vertical position and wherein conveyor means are provided for advancing the blanks in said stack to feeding position, a transfer mechanism for successively removing individual blanks from said stack including a feeding member slideable transversely to the line of advance of said blanks, means for mounting said transfer mechanism for movement in the line of advance of said blanks, stop members carried by said transfer mechanism adapted to rest against the foremost blank in said stack and thereby determine the position of said transfer mechanism, and means actuated by the movements of said transfer mechanism in the line of advance of said blanks for controlling the operation of said conveyor means.

4. In a carton feeding mechanism of the magazine type wherein a supply of collapsed carton

- blanks is supported in a substantially horizontal stack with the blanks on edge in substantially vertical position and wherein conveyor means are provided for advancing the blanks in said stack to feeding position, means for intermittently applying a positive actuating force to said conveyor means to advance said blanks, transfer means for successively removing individual blanks from said stack, said transfer means normally having contact with the foremost blank in the stack, means for mounting said transfer means for movement in the line of advance of said blanks, and means for temporarily rendering said force applying means inoperative to actuate said conveyor means whenever said transfer means is moved beyond a predetermined position in the same direction as the advance of said blanks.

5. In a carton feeding mechanism of the magazine type wherein a supply of collapsed carton blanks is supported in a substantially horizontal stack with the blanks on edge in substantially vertical position, transfer means for successively removing individual blanks from said stack comprising a supporting member mounted for movement relatively to said magazine in the line of advance of said blanks, a feeding member slidably mounted on said supporting member for movement transversely to the line of advance of said blanks and including means for engaging the foremost blank in said stack to slide the same out of said magazine, and means for reciprocating said feeding member relatively to said supporting member.

35. 6. In a carton feeding mechanism of the magazine type wherein a supply of collapsed carton blanks is supported in a substantially horizontal stack with the blanks on edge in substantially vertical position and wherein conveyor means are provided for advancing the blanks in said stack to feeding position, transfer means for successively removing individual blanks from said stack comprising a supporting member mounted for movement relative to said magazine in the line of advance of said blanks, a feeding member slidably mounted on said supporting member for movement transversely to the line of advance of said blanks and including means for engaging the foremost blank in said stack to slide the same out of said magazine, and means for reciprocating said feeding member relatively to said supporting member for controlling the operation of said conveyor means.

55. 7. In a carton feeding mechanism of the magazine type wherein a supply of collapsed carton blanks is supported in a substantially horizontal stack with the blanks on edge in substantially vertical position and wherein means are provided for intermittently advancing the blanks in said stack toward feeding position, transfer means for successively removing individual blanks from said stack comprising a supporting member mounted for movement relatively to said magazine in the line of advance of said blanks, a feeding member slidably mounted on said supporting member for movement transversely to the line of advance of said blanks and including means for engaging the foremost blank in said stack to slide the same out of said magazine, and means for reciprocating said feeding member relatively to said supporting member for temporarily rendering said force applying means inoperative whenever said blank advancing means is inoperative.

10. said supporting member is moved beyond a predetermined position in the same direction as the advance of said blanks.

15. 8. In a carton feeding mechanism of the magazine type wherein a supply of collapsed carton blanks is supported in a substantially horizontal stack with the blanks on edge in substantially vertical position and wherein conveyor means are provided for advancing the blanks in said stack to feeding position, transfer means for successively removing individual blanks from said stack comprising a supporting member mounted for movement relatively to said magazine in the line of advance of said blanks, stop means carried by said supporting member adapted to rest against the foremost carton in said stack and thereby determine the position of said supporting member, a feeding member slidably mounted on said supporting member for movement transversely to the line of advance of said blanks and including means for engaging the foremost blank in said stack to slide the same out of said magazine, and means for reciprocating said feeding member relatively to said supporting member, and means responsive to the movements of said supporting member for controlling the operation of said conveyor means.

20. 9. In a carton feeding mechanism of the magazine type wherein a supply of collapsed carton blanks is supported in a substantially horizontal stack with the blanks on edge in substantially vertical position, transfer means for successively removing individual blanks from said stack comprising a supporting member mounted for movement relatively to said magazine in the line of advance of said blanks, a feeding member slidably mounted on said supporting member for movement transversely to the line of advance of said blanks, and means for reciprocating said feeding member relatively to said supporting member, said feeding member including an element adapted to engage one edge of the foremost blank in said stack to slide the same out of said magazine, and yieldable means for urging said element toward said blank to insure engagement with the edge thereof in spite of variations which may occur in the shape of individual blanks.

25. 10. In a carton feeding mechanism of the magazine type wherein a supply of collapsed cartons is supported in a substantially horizontal stack with the blanks on edge in substantially vertical position, transfer means for successively removing individual blanks from said stack comprising a feeding member reciprocable in a direction substantially parallel to the planes of the carton blanks in said stack, an element carried by said feeding member adapted to engage one edge of the foremost blank in said stack to slide the same out of said magazine when said feeding member is moved in one direction, and yieldable means for urging said element toward said blank to insure engagement with the edge thereof in spite of variations which may occur in the shape of individual blanks.

30. 11. In a carton feeding mechanism of the magazine type wherein a supply of collapsed cartons is supported in a substantially horizontal stack with the blanks on edge in substantially vertical position, transfer means for successively removing individual blanks from said stack comprising a feeding member reciprocable in a direction substantially parallel to the planes of the carton blanks in said stack, an element pivotally mounted adjacent one of its ends on said feeding member, the opposite end of said element having a

portion adapted to engage one edge of the foremost blank in said stack to slide the same out of said magazine when said feeding member is moved in one direction, and a spring interposed 5 between said element and said feeding member for yieldably urging the edge engaging portion of said element toward said blank to insure engagement with the edge thereof in spite of variations which may occur in the shape of individual 10 blanks.

12. In a carton feeding mechanism of the magazine type wherein a supply of collapsed carton blanks is supported in a substantially horizontal stack with the blanks on edge in substantially 15 vertical position, transfer means for successively removing individual blanks from said stack comprising a supporting member pivotally mounted for movement about an axis fixed with respect to said magazine and perpendicular to the line 20 of advance of said blanks, a feeding member slidably mounted for reciprocating movement relatively to said supporting member in a direction transverse to said line of advance of said blanks, and means for maintaining the plane of 25 said feeding member substantially parallel to the planes of the carton blanks in said stack regardless of the position of said supporting member with respect to its pivotal axis.

13. In a carton feeding mechanism of the 30 magazine type wherein a supply of collapsed carton blanks is supported in a substantially horizontal stack with the blanks on edge in substantially vertical position, transfer means for successively removing individual blanks from 35 said stack comprising a supporting arm pivotally mounted for movement about a horizontal axis fixed with respect to said magazine and perpendicular to the line of advance of said blanks, a supporting head pivotally mounted on said 40 arm for movement about a horizontal axis parallel to said first named axis, a feeding member slidably mounted on said supporting head for reciprocating movement in a direction transverse to said line of advance of said blanks, and means including a parallel link system connected 45 to said supporting head for maintaining the plane of said feeding member substantially vertical regardless of the position of said supporting arm with respect to its pivotal axis.

14. In a carton feeding mechanism of the magazine type wherein a supply of collapsed carton blanks is supported in a substantially horizontal stack with the blanks on edge in substantially vertical position and wherein conveyor means 55 are provided for advancing the blanks in said stack to feeding position, transfer means for successively removing individual blanks from said stack comprising a supporting member pivotally mounted for movement about an axis fixed with respect to said magazine and perpendicular to the line of advance of said blanks, a feeding member slidably mounted for reciprocating movement relative to said supporting member in a direction transverse to said line of advance 60 of said blanks, means for continually urging said supporting member about its pivotal axis toward said magazine to bring said feeding member into contact with the foremost carton in said stack, and means operatively connected with said supporting member for temporarily rendering said conveyor means inoperative whenever said supporting member is moved beyond a predetermined position in the same direction as the advance of said blanks.

15. In a carton feeding mechanism of the mag-

azine type wherein a supply of collapsed carton blanks is supported in a substantially horizontal stack with the blanks on edge in substantially vertical position, transfer means for successively removing individual blanks from said stack comprising a supporting member movable relatively to said magazine in the line of advance of said blanks, a feeding member slidably relatively to said supporting member transversely to the line of advance of said blanks, means for continually urging said supporting member toward said magazine to bring said feeding member into contact with the foremost carton in said stack, and means for reciprocating said feeding member relatively to said supporting member regardless 10 of the position of the latter relatively to said magazine.

16. In a carton feeding mechanism of the magazine type wherein a supply of collapsed carton blanks is supported in a substantially horizontal stack with the blanks on edge in substantially vertical position, transfer means for successively removing individual blanks from said stack comprising a supporting member movable relatively to said magazine in the line of advance of said 20 blanks, a feeding member slidably relatively to said supporting member transversely to the line of advance of said blanks and including means for engaging the foremost blank in said stack to slide the same sideways out of said magazine, 30 means for continually urging said supporting member toward said magazine to bring said feeding member into position for engagement with the foremost blank in said stack, stop means carried by said supporting member adapted to rest 35 against said foremost blank, and means for reciprocating said feeding member relatively to said supporting member regardless of the position of the latter relatively to said magazine.

17. In a carton feeding mechanism of the magazine type wherein a supply of collapsed carton blanks is supported in a substantially horizontal stack with the blanks on edge in substantially vertical position, transfer means for successively removing individual blanks from said stack comprising a supporting arm mounted for pivotal movement about an axis fixed with respect to said magazine and perpendicular to the line of advance of said blanks, a supporting head pivotally mounted on said arm for movement about a horizontal axis, a feeding member slidably mounted on said supporting head for movement transversely to said line of advance of said blanks, and means for reciprocating said feeding member relatively to said supporting head regardless 55 of the position of said supporting arm with respect to its pivotal axis.

18. In a carton feeding mechanism of the magazine type wherein a supply of collapsed carton blanks is supported in a substantially horizontal stack with the blanks on edge in substantially vertical position, transfer means for successively removing individual blanks from said stack comprising a supporting arm mounted for pivotal movement about an axis fixed with respect to said magazine and perpendicular to the line of advance of said blanks, a supporting head pivotally mounted on said arm for movement about a horizontal axis, a feeding member slidably mounted on said supporting head for movement transversely to said line of advance of said blanks and including means for engaging the foremost blank in said stack to slide the same sideways out of said magazine, means for reciprocating said feeding member relatively to said supporting 70

75

head regardless of the position of said supporting arm with respect to its pivotal axis, and means carried by said supporting head for preventing the removal from said magazine of more than one blank at each stroke of said feeding member.

19. In a carton feeding mechanism, a magazine for supporting a supply of collapsed carton blanks in a substantially horizontal stack with the blanks on edge in substantially vertical position, conveyor means for advancing the blanks in said stack to feeding position, and transfer means for successively removing individual blanks

from said stack, said magazine comprising a bed plate on which said blank conveyor means are mounted, guide means mounted on said bed plate for guiding said blanks during their advance toward feeding position, means for raising and lowering said bed plate relatively to said transfer means and means for varying the positions of said guide means relatively to said bed plate, the last two of the aforementioned means being adapted to adjust the magazine for use with carton blanks of different sizes. 5 10
